UNITED STATES PATENT OFFICE.

WALTER A. FRANTZ, OF CLEVELAND, OHIO.

LAUNDRY APPARATUS.

Application filed July 24, 1922. Serial No. 577,119.

This invention relates to laundry apparatus especially that of a domestic type and has for its object the provision of a particularly convenient device for use in soaking, rinsing, bluing, starching, etc., as well as in the washing of fabrics of different kinds or colors. The invention is particularly designed for cooperation with a swinging wringer, in which relation it exhibits 10 peculiar advantages, although my improved apparatus is of value apart from any special type of wringer.

In the drawings Fig. 1 is a vertical section and Fig. 2 a top plan view of a device embodying my invention, the latter showing its use with a washing machine; Fig. 3 is a perspective of a slightly modified form; and Fig. 4 is a detail showing a modified valve.

1 represents a round upright tub rotatably mounted on an upright hollow stand or pedestal 2, and centered by a sleeve 3 which depends therein. The casing is formed with a central vertical pipe 4 with which merge the partitions 5 by which the casing is divided into compartments, two, three, four, or more in number as may be desired. The bottom of each compartment is provided with a waste opening 6, which I have shown as closed by a plug 7 as being the cheapest and simplest construction, though any known or suitable device can be used. The interior of the stand or pedestal is formed to constitute a drain passage which receives the lower end of the sleeve 3 and leads to the drain-pipe 8. The pipe 4 terminates below the edge of the casing or of any partition therein so as to permit overflow without spilling onto the floor or into any other compartment.

40 In the preferred species the pipe 4 is made of a size to enable the passage of the pipes 9, 9 whereby hot and cold water is conveyed to the faucets 10, 10, but this can be otherwise effected as shown in Fig. 3.

45 If the device be made of cast iron and afterward enameled as shown in Figs. 1 and 2 it constitutes a very attractive piece of apparatus. To support its weight the upper end of the pedestal may be formed with an annular groove 11 for the reception of bearing balls 12. If the device be made of sheet metal as shown in Fig. 3 the balls may be omitted.

50 It is clear that this device may be used for any laundry purpose, either alone or in connection with other apparatus, and even

when used alone it offers certain decided advantages over the customary wall type of stationary tub in that it is cleaner and more sanitary, produces no dark corners for harboring filth and vermin, and can be more conveniently located with respect to lighting. However the device offers unexpected advantages in connection with other laundry apparatus, especially washing and 60 wringing machines and in particular with a wringer which is pivoted to swing on a vertical axis, regardless as to whether it accompany a washing machine or not.

In Fig. 3 I have shown a wringer comprising a frame 20 carrying a pair of rolls 21 and an individual motor 22 suitably geared thereto, the whole being pivoted on the upright pedestal 23. By locating this pedestal close to the wall of the tub, the 70 wringer can either be swung across the latter so as to wring from any compartment to that on either side thereof, or can be placed tangentially thereof to wring from any compartment into a basket, boiler, or other 75 receptacle. It is not necessary that the motor be carried by the wringer frame or that the wringer be motor driven so far as this combination is concerned, though this is most convenient, but this arrangement 80 saves the former requirement of lifting the wringer bodily from tub to tub.

In Fig. 2 I have shown a washing machine casing 15 having a cylinder 16, and a wringer 17 pivoted to the bracket 18, this 90 bracket being located adjacent the edge of the casing 1 so that the wringer can either be moved to the position shown in full lines to wring from the soaking compartment to the washing machine, or from the latter to the wringing compartment; or it can be swung to the position shown in dotted lines to wring from the rinsing compartment to the bluing compartment; or it can be swung still further around so as to wring from any 95 compartment into a basket or other container.

At 13 in Fig. 1 I have shown a clean out opening or handhole closed by a removable cover 14 to permit cleaning and flushing of 100 the sewer connector in case of need.

In Fig. 4 I have shown a part of my improved laundry apparatus wherein the pipes 9, 9 are connected to a fitting 25 provided with a swiveled spout 26 mounted to turn 110 about a vertical axis so as to enable any compartment to be filled without turning the

2
tub. When two pipes are employed this fitting may be provided with two valves 10^a, 10^a; or the faucets 10, 10 shown in Figs. 1 and 2 may be arranged to swing independently.

It will be understood that many changes in detail can be made within the scope of my invention.

Having thus described my invention what I claim is:

1. A laundry device comprising a hollow pedestal and a unitary tube rotatably supported thereon having a plurality of compartments adapted for the independent reception of liquids, each compartment having an independent discharge outlet which communicates with the interior of said pedestal.
2. A laundry device comprising a tub and means supporting the same for rotation about a vertical axis, an upright central hollow pipe in said tub, and partitions connecting said pipe with the outer wall of said tub and defining liquid holding compartments of which said pipe constitutes the common overflow, there being a separate discharge outlet from the bottom of each compartment.
3. A laundry device comprising a tub and means supporting the same for rotation about a vertical axis, an upright central hollow pipe in said tub, a liquid supply conduit rising through said pipe and having a faucet, and a plurality of spaced partitions connecting said pipe with the outer wall of the casing and defining liquid holding compartments, each of said compartments having a separate outlet from its bottom and also having near its top an overflow into said pipe.
4. A laundry device comprising an upright hollow pedestal, a tub rotatably mounted thereon, a plurality of radiating partitions defining liquid holding compartments, an upright pipe communicating with said pedestal and communicating with all of said compartments at a point above their bottoms and below their sides to constitute an overflow, and a separate bottom-drain for each compartment communicating with the interior of said pedestal.
5. Laundry apparatus comprising, in combination, a tub mounted for rotation about a vertical axis and having a central vertical pipe and a plurality of compartments arranged therearound adapted for the independent reception of liquids, and a supply pipe located in said central pipe and having a swiveled end member adapted to fill any compartment without turning said tub.

6. Laundry apparatus comprising, in combination, a tub mounted for rotation about a vertical axis and having a plurality of segmental compartments adapted for the independent reception of liquids, a supply pipe located inside the limits of the tub and parallel to the casing axis thereof, and a movable spout carried by said pipe adapted to be positioned over any one of said compartments without moving the tub.

7. In combination with a stand, a compartmental tub rotatively secured thereon, said tub having a tube formed in its center, and a water supply pipe passing through the tube in said tub.

8. In combination with a stand, a compartmental tub having a tube formed in its center, a source of water supply passing through said stand and the tube of said tub, said tub rotatively secured to said stand.

9. In combination with a stand having a passage formed therein, a tub having compartments formed therein, a drain positioned in each compartment, and means of fluid communication between said drain and passage.

10. In combination with a compartmental tub having a vertical tube formed therein, a stand having a passage therein in fluid communication with a drain pipe, valved fluid communications between the compartments of said tub and the passage in said stand.

11. In combination with a stand having a drain passage formed therein, a compartmental tub rotatably secured to such stand, a drain being located in each compartment of said tub, which drains are in all positions in fluid communication with said drain passage.

12. In combination with a stand having a pipe formed therein, a tub having compartments formed therein, a drain positioned in each compartment and means of fluid communication between said drain and the pipe formed in said stand.

In testimony whereof, I hereunto affix my signature.

WALTER A. FRANTZ.
